(57) CLAIM

I claim the ornamental design for a face mask with two inner compartments, as shown and described.

DESCRIPTION

FIG. 1 is a front view of the face mask with two inner compartments, shown being worn on the face of a user; FIG. 2 is a side view of the face mask with two inner compartments, shown being worn on the face of a user; FIG. 3 is a front view of the face mask with two inner compartments;

FIG. 4 is a rear view of the face mask with two inner compartments;

FIG. 5 is a top plan view of the face mask with two inner compartments;

FIG. 6 is a bottom view of the face mask with two inner compartments;

FIG. 7 is a top and rear perspective view of the face mask with two inner compartments;

FIG. 8 is a bottom and front perspective view of the face mask with two inner compartments;

FIG. 9 is a left side elevation view of the face mask with two inner compartments;

FIG. 10 is a right side elevation view of the face mask with two inner compartments;

FIG. 11 is a bottom view of the face mask with two inner compartments which has been folded;

FIG. 12 is a top plan view of the face mask with two inner compartments which has been folded;

FIG. 13 is a front view of the face mask with two inner compartments which has been folded; and,

FIG. 14 is a rear view of the face mask with two inner compartments which has been folded.

The broken lines representing a human head in FIG. 1 and FIG. 2 and the areas within them depict environment only and form no part of the claimed design, the broken lines in FIGS. 3-5, 7-10 and 14 represent stitching within the invention and form part of the claimed design.

1 Claim, 7 Drawing Sheets
